William J. Gordan
ATTORNEY.

Patented Sept. 19, 1922.

UNITED STATES PATENT OFFICE.

HORACE BUDD, OF PHILADELPHIA, PENNSYLVANIA.

GRATE BAR.

Application filed January 4, 1921. Serial No. 435,229.

To all whom it may concern:

Be it known that I, HORACE BUDD, a citizen of the United States, residing at the city of Philadelphia, county of Philadelphia, 5 and State of Pennsylvania, have invented a certain new and useful Improved Grate Bar, of which the following is a specification.

The invention has relation to and is an improvement upon the grate bars shown in 10 my United States Letters Patent #778,106 and #837,543 dated December 20, 1904 and December 4, 1906 respectively.

While the grate bars shown in my said 15 patents are so constructed that uninterrupted air space is present between adjacent grate bars nevertheless I have discovered that by increasing the size of such uninterrupted air space the efficiency of the 20 grate as a whole is materially enhanced. To increase such air space however I have found it necessary to effect certain changes in the construction of the grate bars. Heretofore the webs of my grate bars were of comparatively thin cross-section and had a plane 25 surface longitudinally considered. The space between the teeth of the grate bars, which teeth project laterally from such web, according to my former construction ended flush with the plane faces of said web. 30 Therefore, to increase this space it would be necessary to encroach upon the web cross-section with the consequent weakening of the web. According to the present invention I make the web wedge-shaped in cross-section and longitudinally considered I make 35 it curved or fluted and I arrange the teeth, which are in staggered relation, so that a space between adjacent teeth registers with a concaved portion of the web. Thus while 40 the teeth do not exceed the lateral extent of the teeth shown in my said patents the space between adjacent teeth exceeds the lateral depth formerly attained.

The leading object of the present invention 45 resides in the provision of means tending to provide a commercially valuable grate bar possessed of the advantages above enumerated. With this and other objects in view the invention consists of the improvements 50 hereinafter described and finally claimed.

The nature, characteristic features and 55 scope of the invention will be more fully understood from the following description taken in connection with the accompanying drawings forming part hereof, and in which:

Fig. 1, is a view of the underside of so much of a grate bar as is necessary to the understanding of the invention.

Fig. 2, is a view in side elevation of said 60 section of grate bar.

Fig. 3, is an end view of the grate bar, and

Fig. 4, is a fragmentary view, in plan, of 65 a grate bar embodying features of the invention.

For the purpose of illustrating my invention I have shown in the accompanying drawings one form thereof which is at present preferred by me, since the same has been 70 found in practice to give satisfactory and reliable results, although it is to be understood that the various instrumentalities of which my invention consists can be variously 75 arranged and organized and that my invention is not limited to the precise arrangement and organization of the instrumentalities as herein shown and described.

In the drawings 10 designates a web which 80 in cross-section materially increases in width from its base to its top and which longitudinally considered is curved or fluted. Extended laterally from the web, at its thickest or top portion, upon each side thereof, are a plurality of spaced teeth 11 disposed 85 in staggered relation and arranged obliquely with respect to the horizontal axis of the web. A space 12 between adjacent teeth registers with a concaved portion 13 of the web 90 while a convexed portion 14 of the web merges with a tooth 11. Thus a space 12 may be made relatively deep laterally considered to provide a maximum air-space. A convexed portion 14 is considerably thicker 95 at its top than it is at its bottom thus providing a re-enforcement for a tooth. By this construction the web at its top is quite thick and tapers toward its bottom thus providing strength and stability where most needed and at the same time providing for 100 unrestricted air-space of maximum capacity when grate bars are arranged side by side and end to end as in my said patents.

It will now be apparent that I have devised a novel and useful construction which 105 embodies the features of advantage enumerated as desirable in the statement of the invention and the above description and while I have in the present instance shown and described the preferred embodiment thereof 110 which has been found in practice to give satisfactory and reliable results, it is to be un-

derstood that the same is susceptible of modification in various particulars without departing from the spirit or scope of the invention or sacrificing any of its advantages.

5. What I claim is:

A grate bar comprising a web the longitudinal, opposite faces of which present fluted surfaces the convexed portions of said web materially increasing in thickness from 10 the bottom to the top of said web, and a plurality of spaced teeth diverging from the

opposite sides of said web in its thickest parts in staggered relation and so arranged that each space between adjacent teeth registers with a concaved portion of the web, the 15 thickest part of each convexed portion merging upon a curved line with the underside of a tooth to form a reinforcement.

In testimony whereof, I have hereunto signed my name.

HORACE BUDD.
